US0D1019004S

(12) United States Design Patent (10) Patent No.: US D1,019,004 S
(45) Date of Patent: * Mar. 19, 2024

(54) ANIMAL WHELPING BOX PANEL

(71) Applicant: EZwhelp, Inc., Duluth, GA (US)

(72) Inventor: Travis Lynn Fitz, Duluth, GA (US)

(73) Assignee: EZwhelp, Inc., Duluth, GA (US)

() Term: 15 Years

(21) Appl. No.: 29/867,579

(22) Filed: Oct. 28, 2022

Related U.S. Application Data

(62) Division of application No. 29/755,556, filed on Oct. 21, 2020, now Pat. No. Des. 971,511.

(57) CLAIM

The ornamental design for a animal whelping box panel, as shown and described.

DESCRIPTION

FIG. 1 is a front perspective view of a animal whelping box panel;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The dot-dot lines in FIGS. 1-7 depicting various optional components of an animal whelping box panel are included for illustrating environmental structure and form no part of the claimed design.

1 Claim, 5 Drawing Sheets
